UNITED STATES PATENT OFFICE.

MAX SHERS, OF CHICAGO, ILLINOIS.

SHAVING-BRUSH.

No. 864,201.

Specification of Letters Patent.

Patented Aug. 27, 1907.

Application filed November 20, 1906. Serial No. 344,279.

To all whom it may concern:

Be it known that I, MAX SHERS, a citizen of the United States, residing at Chicago, in the county of Cook and State of Illinois, have invented new and 5 useful Improvements in Shaving-Brushes, of which the following is a specification.

This invention is a brush designed particularly for use as a shaving brush.

It has for its object to dispense with hand rubbing 10 commonly resorted to in order to rub the lather in the beard.

A further object is to provide a brush having a circular or orbital motion which will thoroughly mix and rub the lather in such manner as will not tend to throw 15 the same off or out but will gather and work up the lather without irritating the skin.

A further object is to provide a device which can be readily and quickly operated by hand and conveniently applied to all parts of the face, making it a serv- 20 iceable and useful tool for a barber.

The device is also capable of use as a complexion brush or massage instrument.

The invention is illustrated in the accompanying drawings, in which

25 Figure 1 is a longitudinal section thereof. Fig. 2 is a plan view with the back of the casing removed. Fig. 3 is a sectional detail showing the connection between the brush and a connecting rod.

Referring specifically to the drawings, 6 indicates a 30 cupped or dished circular casing to which is fixed a handle 7.

8 indicates a hand crank the spindle 9 of which extends through the back of the casing 6 and is provided within the same with a spur gear 10. This gear meshes 35 with a central gear 11 which in turn meshes with another gear 12, diametrically opposite the gear 10. The gears 11 and 12 are respectively rotatable upon screw pivots 13 and 14 set in a longitudinal supporting bar 15 which is attached at its ends to the side walls of the 40 casing.

A cross supporting bar is indicated at 16, located be- 45 low or in front of the gears above referred to, and to this bar is pivoted a disk wheel 17 which carries a brush

18, the back of the brush being attached to the wheel by means of a stud and screw at 19, said attachment 45 being eccentric to the axis of the wheel. The wheels 10 and 12 have depending crank pins or studs 20 which are connected at their lower ends to a connecting rod 21 which has at the middle a bearing through which the stud 19 on the back of the brush extends. A face 50 plate 22 covers the front of the casing, having at the center an opening 23, large enough for the movement of the brush. The face of the brush is preferably concave so that it will readily conform to the shape of the face.

In operation, rotation of the crank 8 and the gears 10 and 12 causes an orbital motion of the connecting rod 21 which is communicated to the brush, causing said brush to revolve around the pivot of the wheel 17 as an axis, describing an orbital course which closely simulates the movement of the hand or an ordinary brush held in the hand. This movement is better than a rotary movement because it avoids any spattering or throwing off of the lather incident to centrifugal force. It also works up the lather in a comparatively short 60 time, since the gearing produces a rapid motion of the brush. The device is also capable of use as a complexion brush.

I claim:

1. The combination of a frame having a handle, a 70 wheel in the frame, a brush having a projecting stud at the back, eccentrically connected to the wheel, a pair of wheels geared together and having crank pins, a bar connecting the pins and having a bearing through which the stud extends, and means to turn the wheels.

2. The combination of a cupped casing having a handle connected at one side thereof, a wheel in the casing, a brush eccentrically connected to the wheel, so that as the wheel rotates the brush revolves, a hand crank on the back of the casing, a pair of wheels geared together and connected to the crank, and having projecting studs, and a cross bar having a pivotal connection to the studs and the brush.

In testimony whereof I have signed my name to this specification in the presence of two subscribing witnesses. 85

MAX SHERS.
